UNITED STATES PATENT OFFICE.

DAVID STANISLAUS O'DONOVAN, OF VOGELFONTEIN, TRANSVAAL, SOUTH AFRICA,
ASSIGNOR TO O'DONOVAN FURNACES LIMITED, OF JOHANNESBURG, SOUTH AFRICA.

HARDENING STEEL ARTICLES.

Application filed December 9, 1922, Serial No. 605,927, and the Union of South Africa October 7, 1922.

The present invention has reference to heating steel articles for hardening by methods in which the article is magnetically retained in the heating zone and is withdrawn 5 therefrom as the result of loss of magnetism due to heating. This procedure has heretofore been applied to relatively small articles which are heated throughout and which are retained in the heating zone by the magnet 10 opposing the tendency of the article to fall, the article being in direct contact with the magnet; the article falling from the magnet and out of the heating zone upon the non-magnetic point being reached.

15 The process of the present invention is distinguished by the fact that the body under treatment is so supported that its weight has no influence or no substantial influence in withdrawing it; and that an independent 20 withdrawing force is applied, said force preferably being adjustable.

The present process is further distinguished by a part only of the body being heated to the non-magnetic point, whilst the 25 magnet acts not only upon the part of the body which is heated to this degree but also upon the colder part of the body; the withdrawal of the body from the heating zone depending upon a reduction of the total 30 magnetic attraction and not upon the substantially total loss of such attraction.

It is thus possible to arrange for the body to be automatically withdrawn from the 35 heating zone when the local part to be hardened reaches any desired temperature, within a range which includes temperatures substantially above that at which the metal becomes totally non-magnetic; such higher temperatures being necessary for the hardening of alloy steels.

In this latter respect, the invention is particularly applicable to the treatment of long bodies of which the end portions only require to be hardened. Rock drills are 45 examples of such bodies, and it will be seen that when they are provided with working ends of alloy steel, the hardening tempera-

ture of which exceeds the temperature at which it becomes non-magnetic, they can be retained in the furnace by the magnetic attraction on the remainder of the drill after the special alloy end has entirely ceased to be attracted by the magnet.

A furnace for carrying the invention into effect is shown in the accompanying drawings, in which:

Fig. I is a longitudinal view, partly sectioned, of a drill heating furnace constructed according to this invention,

Fig. II is a cross section thereof on the plane 2—2 Fig. I,

Fig. III is a perspective view of the drill supporting and withdrawing mechanism.

1 indicates the furnace structure embodying a grate 2, a combustion chamber 3 and 65 a muffle heating flue 4.

Arranged transversely across the flue are a number of soaking muffles 5, 5^a. These each consist of a tube closed at its inner end 6 and having an exposed open outer end 7 for the insertion of the drill 8. Their internal diameter is but slightly larger than that of the drill so that the latter can readily absorb heat from the tube. The tubes are made massive enough to contain a quantity of heat sufficient to raise the drill point through the desired range without themselves being substantially cooled thereby. The muffles are spaced along the flue 4 so that their respective temperatures are higher 80 the nearer they are to the grate 2; and the drills are placed in them successively to be progressively heated.

The final stage of the heating is effected in the muffles 9, 9^a which are preferably 85 positioned in the combustion chamber 3 in order that the heating in them may be rapidly accomplished. Two final muffles are shown, with a separate row of soaking muffles 5 or 5^a for each of them, the rows 90 being staggered with respect to one another to distribute the heat evenly between them.

The final muffles 9, 9^a are arranged one above and to the side of the other, for

convenience in installing the drill removing mechanism hereafter described; and therefore in order that they may be equally heated, a cornice 10 projects from the furnace structure to deflect the heated gases onto the uppermost muffler 9^a.

For each final muffle there is provided a drill carrier comprising a rod 11 carrying forks 12 and pivotally mounted on the parallel and horizontally moving arms 13. The latter are fixed to spindles 14 mounted in bearings 15 so as to turn with the minimum of friction. The bearings are enclosed in a casing 16 which contains lubricant and protects the bearings from dust. A shield 17 fixed to each spindle 14 prevents dust from entering around the spindle. One of the spindles is fitted with a coil spring 18 the lower end of which engages a fixed part 36 and the other end of which is attached to a cap 19 fixed to the spindle by a pin 20. By taking out the pin 20 and rotating the cap, the tension of the spring can be accurately adjusted; a number of holes 21 being formed 23 in the cap for receiving the pin.

The spring 18 tends to swing the carrier and the drill 8 resting thereon, away from the muffle; the drill being held in place in the furnace by the action of a magnet 22 let into the opposite wall of the furnace and thus out of contact with the hot gases and the drill. The magnet is kept cool by a stream of air or other fluid supplied by a pipe 23. The drill supporting and withdrawing mechanism is made of non-magnetic material.

The last of the soaking muffles 5 is provided with a pocket 24 for a pyrometer 25 the dial 26 of which is conveniently placed 40 for observation by the operator.

The bearing casings 16 are secured to a base 27 which can be shifted on a pedestal 28 towards or away from the furnace to accommodate short or long drills.

45 A signal bell 29 is connected by a lead 30 to an insulated contact 31 which is touched by one of the arms 13 when the latter swing away from the furnace. In so moving the arm pushes the contact aside, and is prevented from touching the same on its return movement by an insulated back 32 to the contact. The second terminal of the bell is earthed.

55 The swinging movement of the arms 13 is limited by adjustable stops 33, 34. The stop 34 nearest to the furnace is mounted on a spring controlled support 35 which enables it to move towards the furnace through a distance of about half an inch.

60 The operation is as follows.—Drills are placed in the soaking muffles 5 or 5^a remote from the fire and are shifted step by step towards the fire by being placed successively in the hotter soaking muffles. Eventually

65 each drill arrives at the final muffle 9 or 9^a,

when it is mounted on the carrier. The latter is swung inwards to bring the drill point against the inner end of the muffle 9 or 9^a, at the same time pressing the support 35 against the spring. The drill is then 70 released sufficiently to enable the spring support to resume its normal position, which retracts the drill from contact with the muffle and prevents it from being unduly heated locally. With the carrier in this position 75 the spring 18 is stressed and thereby tends to withdraw the carrier, but the magnet holds the drill in place. The drill having been heated to within a few degrees of the proper temperature in the last soaking muffle 80 5 or 5^a, reaches the temperature of decalescence soon after being inserted in the final muffle 9 or 9^a. When this occurs the magnetic attraction falls sufficiently to enable the spring 18 to become effective to swing 85 the carrier so as to withdraw the drill from the muffle 9 or 9^a, the spring 18 having been suitably adjusted for this purpose. The attendant,—warned by the ringing of the bell 29,—removes the drill from the carrier and 90 dips it in the cooling fluid.

The pyrometer 25 is employed to make sure that the temperature of the final soaking muffle is such that only a slight additional heating is required in the final muffle. 95

In connection with the foregoing it is to be understood that the magnetic means act to hold the article or body in the heating position until the article or body has reached its decalescent point or condition at which time the movable supporting or holding means withdraws the article or the body.

I claim:

1. The process of heating a magnetic metal body which consists in so movably supporting the body that its movement is not substantially influenced by its weight, retaining the body in a heating zone by the attraction of a magnet on the body, and at the same time applying to the body a force tending to withdraw it from the heating zone. 105

2. The process of heating a magnetic metal body for hardening, which consists in supporting it for movement uninfluenced by its weight, locally heating a portion of the body in a heating zone, retaining the body in position in the heating zone by the attraction of a magnet on it, and at the same time applying to the body a force tending to withdraw it from the heating zone. 110

3. A furnace for heating magnetic metal bodies comprising a heating chamber, a magnet arranged adjacent thereto so as to retain a magnetic body therein, a carrier for the body movable to position the body in and out of the heating chamber, and means for applying to the carrier a retractive force opposing the magnetic force. 125

4. A furnace for heating magnetic metal bodies comprising a heating chamber, a mag. 130

- net arranged adjacent thereto, and a mounting for the body movable towards and from the magnet, said mounting tending constantly to move away from the magnet.
5. A furnace for heating magnetic metal bodies comprising a heating chamber, a magnet arranged adjacent thereto, a mounting for the body, movable to position the body alternatively in or out of the heating chamber, said mounting tending constantly to move away from the heating chamber and the magnet.
6. A furnace for heating magnetic metal bodies comprising a heating chamber, a magnet arranged adjacent thereto, and a carrier mounted on pivoted arms to swing towards and from the magnet and biased to swing therefrom.
7. A furnace for heating magnetic metal bodies comprising a furnace structure, a magnet fixed in relation thereto, a carrier support and a carrier for the body mounted on said support to move towards and from the magnet said support being adjustable towards and from the furnace structure.
8. A furnace for heating magnetic metal bodies comprising a heating chamber, a muffle projecting therein, a magnet adjacent the end of the muffle, a carrier arranged in front of the muffle to support a body in the muffle and movable to withdraw the body from the muffle, said carrier being biased to move away from the muffle and the magnet.
35. 9. A furnace for heating magnetic metal bodies comprising a heating chamber, a muffle projecting therein, a magnet adjacent the end of the muffle, a carrier in front of the muffle to support a body in the muffle and movable to withdraw the body from the muffle, and a stop for limiting movement of the carrier towards the muffle, said stop being spring supported.
10. A furnace for heating magnetic metal bodies comprising a heating chamber, a number of soaking muffles arranged therein to be heated to progressively varying temperatures, a final heating muffle, positioned to attain a higher temperature than the soaking muffles, magnetic means for holding a body in the final muffle, and means tending to withdraw the body from the final muffle.
55. 11. A furnace for heating magnetic metal bodies comprising a heating chamber, a number of soaking muffles arranged therein to be heated to graduated temperatures, a pyrometer for the highest heated of the series, a final heating muffle heated more highly than the last soaking muffle, magnetic means for holding a body in the final muffle, means tending to withdraw the body from the final muffle and signal means actuated by the withdrawing movement.
60. 12. A furnace for heating steel articles for hardening comprising a furnace structure providing a combustion chamber and a flue, several staggered rows of soaking muffles disposed transversely in the flue and corresponding final heating muffles in the combustion chamber.
13. A drill heating furnace comprising a furnace structure providing a combustion chamber and a flue, several rows of soaking muffles disposed along the flue, corresponding final heating muffles in the combustion chamber and disposed at different positions relatively to the fire, and guide means on the furnace structure to deflect hot gases on the rearwardly situated muffle or muffles.
14. The method of heating a magnetic body, which consists in mounting the body for movement to position it in a heating zone or withdraw it therefrom and so that the weight of the body has no material effect on its movement, subjecting it whilst in the heating zone to magnetic attraction tending to retain it in the said zone and simultaneously applying to the body a retractive force which becomes effective to withdraw the body from the heating zone when the body loses magnetism due to heating.
15. A furnace for heat treatment of bodies, comprising a heating chamber, means supporting a body for movement substantially uninfluenced by the weight of the body and so as to position the body in and out of the heating chamber, a magnet arranged to exert magnetic attraction on the body when in the heating chamber, and means for exerting force on the body tending to withdraw it from the heating chamber.
16. The method of heating a magnetic body which consists in supporting the body for movement, exposing only a portion of it to a heating influence, forming a magnetic field, which effectively embraces said portion of the body and adjacent portions, and simultaneously applying to the body a retractive force which becomes effective to withdraw the body from the heating influence upon the magnetic attraction falling due to heating of the body.
17. A furnace for heat treatment of bodies, comprising a heating chamber, means supporting the body for horizontal movement into and from said heating chamber, a magnet arranged to exert magnetic attraction on the body when in the heating chamber, and means for exerting force on the body tending to withdraw it from the heating chamber.
18. A furnace for heat treatment of a body comprising a carrier movable to position the body in and out of a heating position, a heating means acting on the body in the heating position to heat a portion of the body, a magnet providing a magnetic field

which when the body is in the heating position effectively embraces said portion and other portions of the body, and force exerting means tending to withdraw the body 5 from the heating position.

19. In apparatus of the character set forth, the combination with heating means, of movable means for holding an article to be treated in position to be heated by said heating means and means operated by the moving holding means for automatically indicating when said article has reached a desired temperature.

20. In apparatus of the character set forth, the combination with heating means, of movable means for holding an article to be tempered in position to be heated by said heating means, and means operated by said movable holding means for automatically 20 indicating when said article has reached the point of decalescence.

21. In apparatus of the character set forth, the combination with heating means, of a movable means for supporting a magnetic article in a position to be heated by said heating means, and magnetic means that cooperates with the article to hold it in said heating position with the supporting means in a predetermined position and releases said article and its supporting means when the article is heated to substantially its decalescent point.

22. In apparatus of the character set forth, the combination with heating means, of a support for holding an article of magnetic material both during its heating and after it has reached its decalescent condition, and means for magnetically holding the article in a predetermined position during its heating by the heating means releasing it to permit its movement to a different position while still carried by the support when its decalescent condition is reached.

23. In apparatus of the character set forth, the combination with heating means, of a movable support for holding an article of magnetic material both during its heating and after it has reached its decalescent condition, and means for magnetically holding the article in a predetermined position during its heating by the heating means and releasing it to permit its movement to a different position when its decalescent condition is reached, said support being movable 50 to a position to carry the article to said heating position and being held therein by the article until the latter is released by said holding means.

24. In apparatus of the character set forth, the combination with heating means, of a movable support for holding an article of magnetic material both during its heating and after it has reached its decalescent condition, and means for magnetically holding the article in a predetermined position dur-

ing its heating by the heating means and releasing it to permit its movement to a different position when its decalescent condition is reached, said support being movable to a position to carry the article to said heating position and being held therein by the article until the latter is released by said holding means, said support having means for causing its return movement with the article when the latter is released.

25. In apparatus of the character set forth, the combination with heating means, of a pivoted support for holding an article in position to be heated by said means, and magnetic means that operates on an article placed on the support to hold the article and support in a predetermined position while the article is being heated and releases the article when the same reaches the decalescent point to permit the support to swing on its pivot.

26. In apparatus of the character set forth, the combination with heating means, of a swinging support having a saddle for holding a magnetizable article in the zone of said heating means, and magnetic means that operates on said article to hold the article until the temperature thereof makes said article substantially non-magnetic.

27. In apparatus of the character set forth, the combination with heating means, of a movable support for holding a magnetizable article in the zone of said heating means, magnetic means that operates on said article to hold the article until the temperature thereof makes said article substantially non-magnetic, and mechanism operated by the support on its movement for indicating when said article becomes substantially non-magnetic.

28. In apparatus of the character set forth, the combination with heating means, of a movable support for holding a magnetizable article in the zone of said heating means, magnetic means that operates on said article to hold the article until the temperature thereof makes said article substantially non-magnetic, and indicating mechanism actuated by the movement of the support.

29. In apparatus of the character set forth, the combination with a heating furnace having an article receiving chamber, of a support pivoted at one side of the same and having a portion for holding an article in the chamber, means for producing a magnetic condition of the article when in the furnace to hold the support against movement and permit such movement when the article becomes heated to a non-magnetic condition, and a signal operated by said support.

30. In apparatus of the character set forth, the combination with a furnace, of an article support pivotally mounted alongside the furnace, and magnetic means for holding a

magnetic article on the support in a position to be heated by the furnace, said means becoming inactive on the article when the latter reaches the decalescent point.

5. 31. In apparatus of the character set forth, the combination with a furnace, of an article support mounted on one side of the furnace,

and magnetic means on the other side of the furnace for holding a magnetic article on the support in a position to be heated by the furnace, said means becoming inactive on the article when the latter reaches the decalescent point.

DAVID STANISLAUS O'DONOVAN.
